SPIT FOR SMOKERS' PIPES

James T. McClenahan, Washington, D. C.

Application October 31, 1931. Serial No. 572,377

20 Claims. (Cl. 131—12)

The present invention is a spit for smokers' pipes, and is useful in supporting the pipe on the ground or other soft surface which may be penetrated by the spit.

It is a known fact that participants in outdoor sports frequently smoke pipes while participating in a game, but while executing a play find it desirable and convenient to lay the pipe upon the ground. It frequently occurs that the 10 tobacco in the pipe will fall from the pipe bowl due to the fact that the pipe does not always assume its proper position to hold the tobacco therein and if the tobacco is afire damage to the grass or even greater subsequent damage often 15 results. Moreover, after the player has executed the play, he will forget the pipe and leave it where it has been laid due, possibly, to the fact that the pipe lying close to the ground is inconspicuous and not noticed. Furthermore, by laying 20 the pipe on the ground, the mouthpiece of the pipe or stem becomes dirty which is disagreeable and insanitary when placed in the mouth.

The object of the present invention is to provide 25 a pipe with a means which may be stuck into the ground or other surface for supporting the pipe in proper position so as to prevent the tobacco in the bowl from falling out and which will maintain the mouthpiece of the stem in a position from becoming dirty and 30 which will also hold the pipe in the position above the surface of the ground so that it may be more readily noticed either by the owner of the pipe or others, thereby preventing accidental 35 loss.

It is also an object of the invention to provide 40 such a means in the form of a spit which is extremely inexpensive but yet efficient and durable in use and which may be attached to the bowl end portion of the pipe or to the stem portion adjacent the bowl and which is so constructed 45 as to be readily attachable and detachable and which is extremely light so as to add a minimum of weight to the pipe.

Another object of the invention is the provision 50 of a smoker's pipe spit which may be moved into and out of operative position.

With the above and other objects in view, the 55 invention resides in the sundry details of construction, combination and arrangement of parts hereinafter more fully described and pointed out in the appended claims.

In the drawing, which shows several examples 60 of embodiments by which the invention may be practiced,

Figure 1 is a perspective view of a pipe having one end of a spit attached to the bowl thereof and stuck into the ground and also illustrating the position the pipe will assume when supported by the spit;

Figure 1a is a modified construction of the spit means shown in Figure 1;

Figure 2 is a fragmentary view of the bowl end of a pipe having a modified form of spit attached thereto;

Figure 3 is a front end view of the bowl of a pipe equipped with the spit shown in Figure 2;

Figure 4 is a side view of a pipe having a further modified form of spit attached thereto;

Figure 5 is a sectional view taken substantially 70 on line 5—5 of Figure 4;

Figure 6 illustrates another modified embodiment of the invention, and

Figure 7 illustrates another modified embodiment of the invention.

Referring in detail to the drawing, in which like characters refer to similar and like parts throughout the several views, Figure 1 shows a pipe P having a bowl portion b and a mouthpiece m. From the bottom portion of the bowl

b a spit 10 forwardly extends and which comprises a slender pointed rod having means 11 provided on one end for securing the spit to the bowl. This means may comprise a screw threaded end, as shown in Figure 1, or a split

end 11c, as shown in Figure 1a, which may be inserted into an opening in the bowl of the pipe, or may be attached in any other suitable manner. The said opening in the pipe may have a bushing fitted therein, which bushing in Figure 1 is internally threaded, as at 11a, to co-operate with the threads 11 on the end of the spit, or the bushing may not be threaded, but of such size as to frictionally receive the split end 11c of the spit so as to firmly bind the latter

therein. The bushing may also comprise the opened end of an elongated sleeve, suitably embedded in or otherwise carried on the pipe stem to form a sheath into which a spit 10 may be received and housed when not in use. The

knurled end 11b of the spit in Figure 1, and 11c in Figure 1a provides a finger piece, facilitating its removal from its housed position in the sheath.

With reference to Figure 2, the spit is shown 105 as comprising a slender pointed rod 10a having at its upper end two oppositely disposed clamping jaws 12. Each jaw is relatively wide with respect to the bowl of the pipe and shaped

to conform to the side surface of the pipe so 110

that the pipe may be received between the opposite jaws 12 and held in position. It is preferable to form these jaws of resilient wire which is bent in the form of a loop and which has its 5 end portions, or at least one portion twisted, as at 13, about the corresponding end portion of the opposite loop, one of the end portions protruding a greater distance to form the spit 10a.

In this form of the invention, the jaws will 10 normally assume the dotted line position shown in Figure 3 and when the bowl of the pipe is inserted between the jaws, the resiliency of the metal will firmly grip the sides of the pipe. Of course it will be understood that these jaws may 15 be bent by the hand to readily accommodate the device to pipes of slightly varying size.

When it is desired to use the spit for supporting the pipe on the ground or like surface, it 20 may be shifted to the full line position shown in the drawing and when it is desired to place the same in the pocket it may be shifted to the dotted line position without being entirely removed from the pipe. However, it will be understood that the spit can be readily detached 25 if desired.

Another form of the invention is shown in Figures 4 and 5 wherein the spit comprises an elongated slender rod 10b which has its upper end formed into several convolutions 14 providing a resilient coil disposed between the spaced projecting ears 15 on the resilient clip member 16. This clip member is in the form of a split ring adapted to engage about the stem of the pipe at a point adjacent its bowl. The 30 spit is held in position on the clip by a pin 17 which extends through the ears 15 to the convolutions 14. The outward-extending ears 15 of the clip are to bear endwise against the coil formed by the convolutions 14 and are held frictionally in this position by the pin 17 which is preferably headed at both ends. It will be manifest that the spit may be collapsed to occupy the position close against the side of the pipe stem and substantially parallel therewith 35 as shown in the dotted lines of Figure 4 in order that the pipe may be readily carried in the pocket without unnecessary and objectionable projection; or it may be moved to the full line position for the purpose of supporting the pipe 40 in position. In this form of the invention it is proposed to have one end 18 of the coil 14 project tangentially therefrom so as to form a stop which will be brought to bear against the surface of the pipe stem when the spit is in 45 its full line position so as to limit it in its opening movement and to give it greater purchase against the surface of the stem.

In Figure 6, still another modified form of the invention is illustrated where in the spit 10c is 50 made integral with the pipe bowl and projects outwardly therefrom.

The form of invention shown in Figure 7 provides for a collapsible spit 10d as shown in Figure 4 but attached to a bowl engageable clip 55 or attaching device 12a. This clip 12a may be formed of wire or sheet material provided with ears 15a, similar to the ears 15 in Figures 4 and 5, between which the coil end 14a of the spit 10d is disposed, as previously described.

In all of the examples illustrated, the essential 60 feature of the invention is employed. However, it may be embodied in numerous other forms and the examples herein shown are merely for the purpose of illustration. Therefore it is to 65 be understood that the invention is susceptible

to numerous changes in forms and embodiments as fall within the scope of the appended claims.

What is claimed:

1. A supporting spit for smokers' pipes comprising a slender spit member, resilient means on one end portion of the spit member adapted to receive the bowl of a smoker's pipe and including a pair of spaced oppositely disposed jaws each formed of a loop of wire, the end portions of said loops being secured together and one of said end portions, at least, being extended to form an elongated slender spit member.

2. A spit for smokers' pipes including a slender spit member having its upper end convoluted into a coil, means for securing said spit to the pipe having two spaced lugs thereon between which the coil end of the spit is disposed in frictional contact therewith, and a pin extending through said lugs and through the coil and spit.

3. A spit for smokers' pipes including a slender spit member having its upper end convoluted into a coil, means for securing said spit to the pipe having two spaced lugs thereon between which the coil end of the spit is disposed in frictional contact therewith, and a pin extending through said lugs and through the coil and spit, the free end of said coil extending tangentially therefrom to form a stop in the operating movement of said spit.

4. The combination with a smoker's pipe, of a spit detachably carried by the pipe and capable of supporting the pipe from a surface penetratable by the spit, and a sheath carried by the pipe to house the spit when detached from its operative position.

5. A supporting spit for smokers' pipes comprising a slender spit member and a sheath therefore, said sheath being adapted to be carried by said pipe, and cooperating means on one end of the spit and sheath respectively for maintaining said spit within the sheath and for supporting it in operative position therefrom.

6. A support for smokers' pipes having a bowl and a rigid pipe stem, said support comprising a slender spit member projecting from the base of the bowl in a generally forward direction of the pipe.

7. The combination with a smoker's pipe having a socket opening in the bowl thereof, of a spit member having one end capable of penetrating a surface and the other end detachably supported in said socket member for supporting the pipe from said surface.

8. The combination with a smoker's pipe having a socket opening in the bowl thereof, of a spit member having one end capable of penetrating a surface and the other end detachably supported in said socket member for supporting the pipe from said surface, the penetrating end of said spit being receivable in said socket when the spit is reversed in position, whereby said penetrating end may be housed or protected.

9. In combination with a smoker's pipe comprising a bowl having a rigid stem extending angularly from its axis, the outer end of said stem providing a mouth piece receivable in and supporting the pipe from the smoker's mouth, of a support for the pipe mounted thereon and including a slender spit member projecting from a lower portion of the pipe adjacent the bowl thereof and extending forwardly of the pipe and positioned below the mass center of said pipe whereby its pointed end is adapted to penetrate a surface, when the pipe is dropped upon said

- surface, for supporting the pipe thereon with its bowl upright and its stem out of contact with said surface.
10. In combination with a smoker's pipe comprising a bowl having a rigid stem extending angularly from its axis, the outer end of said stem providing a mouth piece receivable in and supporting the pipe from the smoker's mouth, of a support for the pipe mounted thereon and including a slender spit member projecting outwardly from a lower portion of the pipe adjacent the bowl thereof so that the pointed end of the spit will penetrate a surface below the pipe and the shank thereof provide a leg supporting the bowl in substantially upright position and the mouth piece out of contact with said surface.
11. A supporting spit for a smoker's pipe comprising a slender spit member having a bifurcated upper end, the bifurcated portions being resilient and having their opposing faces curved longitudinally and laterally to receive the bowl of a smoker's pipe.
12. In combination with a smoker's pipe comprising a bowl having a rigid stem extending angularly from its axis, the outer end of said stem providing a mouth piece receivable in and supporting the pipe from the smoker's mouth, of a support comprising a slender spit member projecting from the base of the bowl in a generally forward direction of the pipe.
13. In combination with a smoker's pipe comprising a bowl having a socket opening therein and a rigid stem extending angularly from its axis, the outer end of said stem providing a mouth piece receivable in and supporting the pipe from the smoker's mouth, of a spit member having one end capable of penetrating a surface and the other end detachably supported in said socket member for supporting the pipe from said surface.
14. In combination with a smoker's pipe comprising a bowl having a socket opening therein and a rigid stem extending angularly from its axis, the outer end of said stem providing a mouth piece receivable in and supporting the pipe from the smoker's mouth, of a spit member having one end capable of penetrating a surface and the other end detachably supported in said socket member for supporting the pipe from said surface, the penetrating end of said spit being receivable in said socket when the spit is reversed in position, whereby said penetrating end may be housed or protected.
15. In combination with a smoker's pipe comprising a bowl having a rigid stem extending angularly from its axis, the outer end of said stem providing a mouth piece receivable in and supporting the pipe from the smoker's mouth, of a supporting spit for said pipe comprising a slender spit member having a bifurcated upper end, the bifurcated portions being resilient and having their opposing faces curved longitudinally and laterally to receive the bowl of a smoker's pipe.
16. In a combination with a smoker's pipe comprising a bowl having a rigid stem extending angularly from its axis, the outer end of said stem providing a mouth piece receivable in and supporting the pipe from the smoker's mouth, of a supporting spit for said pipe comprising a slender spit member, resilient means on one end portion of the spit member adapted to receive the bowl of a smoker's pipe and including a pair of spaced oppositely disposed jaws each formed of a loop of wire, the end portions of said loops being secured together and one of said end portions, at least, being extended to form the elongated slender spit member.
17. In a combination with a smoker's pipe comprising a bowl having a rigid stem extending angularly from its axis, the outer end of said stem providing a mouth piece receivable in and supporting the pipe from the smoker's mouth, of a spit for said pipe including a slender spit member having its upper end convoluted into a coil, means for securing said spit to the pipe having two spaced lugs thereon between which the coil end of the spit is disposed in frictional contact therewith, and a pin extending through said lugs and through the coil of the spit.
18. In a combination with a smoker's pipe comprising a bowl having a rigid stem extending angularly from its axis, the outer end of said stem providing a mouth piece receivable in and supporting the pipe from the smoker's mouth, of a spit for said pipe including a slender spit member having its upper end convoluted into a coil, means for securing said spit to the pipe having two spaced lugs thereon between which the coil end of the spit is disposed in frictional contact therewith, and a pin extending through said lugs and through the coil of the spit, the free end of said coil extending tangentially therefrom to form a stop in the operating movement of said spit.
19. In a combination with a smoker's pipe comprising a bowl having a rigid stem extending angularly from its axis, the outer end of said stem providing a mouth piece receivable in and supporting the pipe from the smoker's mouth, of a spit detachably carried by the pipe and capable of supporting the pipe from a surface penetrable by the spit, and a sheath carried by the pipe to house the spit when detached from its operative position.
20. In a combination with a smoker's pipe comprising a bowl having a rigid stem extending angularly from its axis, the outer end of said stem providing a mouth piece receivable in and supporting the pipe from the smoker's mouth, of a supporting spit for said pipe comprising a slender spit member and a sheath thereof, said sheath being adapted to be carried by said pipe, and cooperating means on one end of the spit and sheath respectively for maintaining said spit within the sheath and for supporting it in operative position therefrom.
